UNITED STATES PATENT OFFICE.

ELOF R. LEONARD, OF MOUNTAIN LAKES, NEW JERSEY.

WASTE CHUTE.

Application filed February 1, 1922. Serial No. 533,203.

To all whom it may concern:

Be it known that I, ELOF R. LEONARD, a citizen of the United States, residing at Mountain Lakes, Morris County, New Jersey, have invented certain new and useful Improvements in Waste Chutes, of which the following is a specification.

My invention relates to that class of waste chutes which are intended for use in manufacturing and commercial establishments where waste paper and packing material and the waste products of manufacture and the like accumulate so as to require some simple and efficient means for their convenient and safe removal. For such purposes chutes of fire proof material are extended from one floor to another of the building, being provided with suitable intake openings at various intake points through which the waste material may be injected, to fall down to the bottom of the chute. And my improvements are directed particularly to means for closing and opening such intake openings, so as to guard against the danger of back draughts, fire in the chute, and the like, without obstructing the main channel of the chute.

Details of my improvements I will now proceed to point out and explain, referring in so doing to the accompanying drawings in which Fig. 1 is a front elevation of a portion of a chute showing the outer door, the counterbalancing means being shown in broken lines; Fig. 2 is a vertical sectional view of the same taken as on the line 2—2 of Fig. 1 looking to the left, the chute being prolonged vertically further than in Fig. 1; and Fig. 3 is a cross sectional view taken on the line 3—3 of Fig. 2 looking down.

Similar reference numerals designate similar parts in all the figures.

A fire proof chute 1 made, for instance, of sheet metal is, preferably, built into a wall 2, and extended down through the building, being provided with suitable clearing means, (not shown), at its lower portion, in a well-known manner.

In the front of the chute, and preferably near the level of a floor 4, I form an intake opening 5 which is covered by a cowl or hopper embodying an inwardly sloping bottom 6, sides 7—7 and an outwardly sloping top 8.

I prefer to form this hopper of sheet metal and to provide the sides with flanges 9—9; 55 and also to provide the lower edge of the outwardly sloping top 8 with an upturned lip 10.

Adjacent to and extending above the opening 5 I form on each side a guide 11, preferably of the material of the sides 7—7, so that channels 12—12 are formed between the guides and the sides of the chute adjacent to the opening 5. In these channels 12—12 is placed a vertically sliding door 13 which 65 will completely close the opening 5 when lowered.

On the front of the hopper I mount another sliding door 14 which is provided with inturned edges 15—15 adapted to slidably 70 engage around the flanges 9—9 on the sides of the hopper so that the door may be slid up and down thereon. This door is also preferably provided with an inwardly and downwardly turned upper edge 16 which is 75 adapted to enter behind the upturned lip 10 on the portion 8 of the hopper when the door is lowered, so as to make a snug joint therewith.

The bottom of the door 14 is provided 80 with suitable means, for instance a grooved flange 17, for engaging with the upper edge 18 of the bottom 6 when the door 14 is lowered, as shown in the figures.

Near the top of the hopper casing I mount 85 a pulley wheel 19 over which travels a chain 20, one end of which is connected through a suitable, fusible link 21 with the door 14, while the other end is similarly connected through another fusible link 22 with the 90 door 13; the chain being of such a length and so adjusted that when the door 14 is pulled down, as shown in the figures, the door 13 will be raised to uncover the opening 5; and when the door 14 is slid up, so as to uncover 95 the opening in the front of the hopper, the door 13 will be lowered so as to cover the opening 5.

When it is desired to pass material into the chute, the outer door is raised, and the 100 inner door simultaneously closes, cutting off any backdraught up the chute, and preventing annoyance by dust and the like, which might be caused if waste material was passing down the chute from a higher point. 105 The material to be disposed of is then placed

- in the hopper, after which the outer door is pulled down, thereby raising the inner door and allowing the material to slide out of the hopper into the chute; so that excepting 5 during the brief time when the doors are opening and closing, the chute will be closed off by either the inner or the outer door, and this will be accomplished without in any way obstructing the main channel of the chute 10 so as to interfere with its use from points higher up in it.

Owing to the inflammable nature of the material which is ordinarily passed down such chutes, and the possibility of fire originating in the material and flaring up the chute, it is highly important to provide extra means for confining any such blaze within the chute and preventing its escape through the hopper into the building. This 15 end is gained by the use of fusible links in the chain 20, one preferably near the bottom of the door 13 and another near the bottom of the door 14, which are points so situated that flames coming up the chute would 20 quickly reach them. The melting of either of these fusible links will release both doors, allowing whichever of them is lifted, or both of them if partially raised, to slide down of their own weight and thus close 25 both the opening into the hopper and the opening into the chute, interposing in this way a double barrier between any fire in the chute and the portion of the building adjacent to the exterior of the hopper.

30 For convenience in assembling, I prefer to provide the main portion of the chute 1 with a pair of flanges 23, 23, which may be united thereto and which will form between them and the outer face of the chute 1 35 grooves into which the side flanges 24, 24 of the hopper may be slid, thus permitting of setting up the vertical chute first and then readily attaching the hopper thereto without the inconvenience of riveting the 40 hopper to the chute.

I have illustrated the use of a chain provided with fusible links as a means for counterbalancing the doors, but it will be readily understood that other means which 45 would be destroyed or released by the heat of the fire in the chute so as to allow the doors to fall, would be within the scope of my invention, as would also be other modifications, by the use of mechanical equivalents or the like, such as would suggest themselves to one skilled in the art.

Having thus described my invention, what I claim and desire to secure by Letters Patent of the United States is:—

- 60 1. The combination, with a waste chute, of an outwardly extended hopper, a slide- 125 able door for closing the intake opening into the hopper, a slideable door for closing the outlet from the hopper into the chute, and means connecting the two doors so that the

movement of the outer door in one direction will produce a reverse movement of the inner door.

2. The combination, with a waste chute, of an outwardly extended hopper, a slide- 70 able door for closing the intake opening into the hopper, a slideable door for closing the outlet from the hopper into the chute, and means consisting of a flexible, counter- 75 balancing element connecting the two doors so that the movement of the outer door in one direction will produce a reverse movement of the inner door.

3. The combination, with a waste chute, of an outwardly extended hopper, a slide- 80 able door for closing the intake opening into the hopper, a slideable door for closing the outlet from the hopper into the chute, and means consisting of a flexible, counter- 85 balancing element, provided with portions fusible at a comparatively low temperature, connecting the two doors so that the movement of the outer door in one direction will produce a reverse movement of the inner door.

90 4. The combination, with a waste chute, of an outwardly extended hopper, a vertically slideable door for closing the intake opening into the hopper, a vertically slideable door for closing the outlet from the 95 hopper into the chute, and means connecting the two doors so that the movement of the outer door in one direction will produce a reverse movement of the inner door.

5. The combination, with a waste chute, 100 of an outwardly extended hopper, a slideable door for closing the intake opening into the hopper, a slideable door for closing the outlet from the hopper into the chute, and counterbalancing means connecting the two 105 doors so that the movement of the outer door in one direction will produce a reverse movement of the inner door.

6. The combination, with a waste chute, 110 of an outwardly extended hopper, an outer door for the hopper, an inner door for the hopper vertically movable in a straight line in its own plane, and means for causing the movement of the outer door to open the inner door.

115 7. The combination, with a waste chute, of an outwardly extended hopper, an outer door for the hopper, an inner door for the hopper limited in its movement to space outside of and parallel to the chute, and means for causing the movement of the outer door to produce a reverse movement of the inner door.

8. The combination, with a waste chute, of an outwardly extended hopper, an outer 125 door for the hopper, an inner door for the hopper limited in its movement to space outside of the chute, and means, embodying an element fusible at a comparatively low temperature, for causing the movement of 130

the outer door to produce a reverse movement of the inner door.

9. The combination, with a waste chute, provided with an intake opening therein and a guide member near each side of the opening forming a longitudinal groove between such member and the chute, of a hopper provided with longitudinal edge flanges

adapted to be slipped within and held by said grooves.

10. The combination, with a waste chute provided with an intake opening and with hopper engaging means, of a hopper provided with means for slidably engaging with said hopper engaging means.
